UNITED STATES PATENT OFFICE.

WILLIE F. BOGART AND FRANK K. HOTTAL, OF WILMINGTON, NORTH CAROLINA.

DESIGN FOR AN ADVERTISING-CABINET.

42,726.

Specification for Design.

Patented July 9, 1912.

Application filed March 6, 1912. Serial No. 682,026. Term of patent 14 years.

To all whom it may concern:

Be it known that we, WILLIE F. BOGART and FRANK K. HOTTAL, citizens of the United States, residing at Wilmington, in the county of New Hanover and State of North Carolina, have invented a new, original, and ornamental Design for Advertising-Cabinets, of which the following is a specification, reference being had to the drawing forming a part thereof.

The figure is a perspective view of an advertising cabinet illustrating our new design.

We claim:

The ornamental design for an advertising cabinet as shown.

WILLIE F. BOGART.
FRANK K. HOTTAL.
